(No Model.)

C. H. POND.

AUTOMATIC SIGNALING DEVICE FOR TIME SERVICE.

No. 408,846.

Patented Aug. 13, 1889.

UNITED STATES PATENT OFFICE.

CHESTER HENRY POND, OF CHICAGO, ILLINOIS, ASSIGNOR TO THE SELF WINDING CLOCK COMPANY, OF NEW YORK, N. Y.

AUTOMATIC SIGNALING DEVICE FOR TIME-SERVICE.

SPECIFICATION forming part of Letters Patent No. 408,846, dated August 13, 1889.

Application filed May 3, 1889. Serial No. 309,429. (No model.)

To all whom it may concern:

Be it known that I, CHESTER HENRY POND, a citizen of the United States, residing in Chicago, in the county of Cook and State of Illinois, have invented certain new and useful Improvements in Automatic Signaling Devices for Time-Service, of which the following is a specification.

The object of the invention is to provide means whereby the preliminary signals for the transmission of time over an electric circuit and the synchronizing or other correction of time-pieces included in said circuit may be given with greater accuracy than heretofore.

The invention will be readily understood by an inspection of the accompanying drawing, which illustrates the operative parts of an instrument embodying the invention, with the electric circuits in diagram.

In order to understand the invention and operation of the devices, a description of the present method of transmitting time-signals generally employed upon the principal lines of railways will be necessary. These signals are now sent by the hand of the operator at the central station. The devices here described are intended to take the place of the manual operations.

The railroad time-service is generally performed at the hour of ten in the forenoon, and consists of the following operations: At 9.57 the operator at the central station opens his key and writes the word "time" in Morse characters slowly during fifty seconds, when there is a pause of ten seconds. At 9.58 the operator again opens his key and writes the letter "I" in Morse characters (consisting of two dots) slowly for fifty seconds, when he allows another pause of ten seconds. At 9.59 the operator turns a switch which throws the standard clock into the circuit. This clock then, by the devices connected therewith, opens and closes the circuit once each second for fifty seconds, and then leaves the circuit open for another pause of ten seconds, and at precisely ten o'clock the standard clock closes the circuit one full second. The impulses thus transmitted over the line are for the correction and synchronizing of the va-

rious clocks in the circuit. Lastly, after this close of the circuit for one full second, the signaling operator repeats three times the letter "S" in Morse characters, followed by the numerals 10, and closes the circuit, after which the ordinary business of the line is resumed.

Referring now to the drawing, it will be explained how the devices illustrated are arranged to perform the operations described with comparatively little labor on the part of the operator. The main line L may be traced from the ground at G through the main battery O and the switch S. As shown in the drawing, none of the time-transmitting devices are in circuit.

The operative part of the instrument for transmitting the preliminary signals is shown at A. It consists of a train of wheels driven by the weight W, and motion is thereby given to the wheel B at such a rate as to revolve once in fifty seconds in the direction indicated by the arrow. It is prevented from turning by the pin p resting against the upper end of the lever l, which forms part of the key K. Upon the shaft C are three disks D, E, and F, insulated from each other, but all in electrical connection with the shaft C, and this latter is connected by the wire L' with the main line L.

The operation of transmitting the signals is as follows: At a second or two preceding the hour 9.57 by the standard clock the operator turns the switch S so that it rests upon the point s. This puts in circuit the wire 1 and the insulated spring n, which is in contact with the disk D. At precisely 9.57 the operator depresses the key K. This releases the wheel B, which turns under the stress of the weight W and its connected train, and, being geared to the shaft C, the disks D and E and F are all revolved therewith. The disk D has cut upon its periphery, as will be seen, the Morse letters "time," and this disk is revolved several times by one revolution of the wheel B. The result is that the telegraphic word "time" is automatically repeated over the line with entire regularity until the pin p on the wheel B again meets with the top of the arm l upon the key K. The operator then

turns the switch S from the point s to the point s' . This connects with the line through the wire 2 and the spring n' , which is in contact with the disk E. At precisely 9.58 the 5 operator again depresses the key K, which releases the wheel B, as before, and the connection is made through the disk E with the lines I' and L. The disk E has upon its periphery the Morse character "I," and this will, 10 therefore, be repeated regularly during the time the wheel B makes a revolution—that is, fifty seconds—at the end of which time the pin p again meets the end of the arm L. The operator then turns the switch S from 15 the point s' to the point s^2 . This throws into the circuit the devices connected with the standard clock, which is represented at T. The clock itself is in a local circuit l' , which includes the battery O and the electro-magnet M. The armature m of this electro-magnet is connected to the main line L by the line L^2 . The stop R, against which the armature m is brought when attracted by the magnet, is connected with the point s^2 by the 20 line L^3 . The devices V, connected with the armature m , are intended to relay the signals given by the clock T over the local circuit l' and to increase the time that the main circuit shall remain closed for the transmission 25 of the clock-signals. These devices consist of a train of wheels operated by the weight W' and the levers X and Y. The lever Y, pivoted at y and pressed downward by means of a spring y' , has one end resting upon the 30 top of the armature-lever m' while the armature is in its back position. A second lever X, pivoted at x , has its free end resting upon a projection upon the armature-lever, as shown. The spring S tends to hold the armature 35 in a position away from the magnet.

The signals sent by a standard clock are always made as brief as possible, so that the rate of the clock shall not be affected by its operating any device to keep a circuit closed 40 for any considerable length of time. The relay herein described is intended to lengthen the signals of the clock sufficiently to make them operative over the long line.

The operation is as follows: When the local 45 circuit l' is closed by the clock, the armature m is attracted, the armature-lever is brought against the stop R, and the main battery O is thrown to line. The clock-signals are so exceedingly brief that they would fail to be 50 operative throughout the circuit; but the time of closing the circuit is lengthened by the operation of the two levers Y and X, for as soon as the armature is brought up to the magnet and the circuit-closing point at the 55 upper end of the armature-lever is brought against the stop R the end of the lever Y drops behind the armature-lever and rests upon the pin p' . At the same time the end of the lever X is released and it is im- 60 mediately caused to revolve by means of the weight W' and its connected train, which

gears with a pinion upon the shaft x . The lever X is at one side and therefore clear of the lever Y; but connected with the lever X is the cam X' , which revolves therewith. As 70 the cam revolves it strikes the pin p^2 upon the lever Y' and throws the latter upward and out of the way of the armature-lever. The pin p^2 limits the upward movement of the lever Y. As soon as it has passed above 75 the end of the armature-lever, the circuit having previously been opened by the clock, the spring S draws the armature-lever back, the lever X passes over and strikes upon the projection upon the armature-lever, and the devices come to rest in the position shown in the drawing. This is repeated each second, and the length of time that the main circuit is thus closed depends upon the time which it takes the lever X and its connected cam 80 to revolve. Thus, if the clock closes the circuit, say, but one-twentieth or one-tenth of a second, the devices described can easily be arranged to hold it closed, while thus relay- 85 ing it, for one-fourth or one-half a second. 90 The clock having now performed its functions of distributing its time upon the circuit, the operator, as soon as the last or ten-o'clock signal has been given by the clock, turns the switch S upon the point s^2 and depresses the 95 key K. This sends the current through the wire 3 and the spring-lever n^2 to the disk F, which has upon its periphery the Morse characters SSS, followed by the numerals 10. The rest of the periphery of this disk is cut away, 100 so that as soon as the numerals last named are transmitted the circuit is opened, when the operator again turns the switch S to its original position, as shown in the drawing. The line is then free for the resumption of 105 ordinary business. It will be seen from this that a large part of the manual operations of the operator have been done away with, and regularity and accuracy are given both to the preliminary and the final signals connected 110 with the operation of the distribution of time, while the clock-signals themselves are relayed in such a manner as to give them firmness and insure their certain transmission over a long line. 115

I claim as my invention—

1. The combination of a main line having secondary time-pieces included therein, the branch lines 1, 2, and 3, the disks D, E, and F, respectively connected with said branch lines, clock-work for revolving said disks, and the line I' , connecting said disks with said main line. 120

2. The combination of a clock-work, the wheel B, forming a part thereof, the insulated disks D, E, and F, as described, the key K, for releasing said clock-work, and the lines 1, 2, and 3, and I' , for connecting said devices with a telegraph-line. 125

3. The combination of a main line of tele- 130 graph having secondary time-pieces included therein, the standard clock T, with its local

circuit, and the relay devices, as described, consisting of a train of wheels and the levers X and Y, operating as described.

4. The combination of a main line, the 5 switch S, the instrument A, for sending the preliminary signals for time-service, consisting of a train of wheels, of which the wheel B forms a part, the device for stopping and releasing said wheel, as the pin p and the key 10 K, and the disks D, E, and F, operated by

said train, the standard clock and its local circuit, the lines L² and L³, and the relaying devices V, substantially as described.

In testimony whereof I have hereunto subscribed my name this 20th day of April, A. D. 15 1889.

CHESTER HENRY POND.
